KEYHOLE COVER

Theodore H. Johnstone, Detroit, Mich., assignor to The Yale & Towne Manufacturing Company, Stamford, Conn., a corporation of Connecticut

Application May 25, 1944, Serial No. 537,243.

15 Claims.

(Cl. 70—455)

This invention relates to a key hole cover for a lock, and is an improvement over the invention disclosed in my patent No. 2,355,300 for a Key hole cover and assembly.

In my patent I disclose a key hole cover and assembly particularly adapted to prevent the entrance of rain or snow into a keyway, and to facilitate the escape of water or condensation from the keyway. The invention of the said patent embodies a shutter that is mounted on the front of the lock and is adapted to move into and out of covering relation to the keyway of the lock. An important feature of the said invention resides in the manner in which the swinging shutter cooperates with the surface outlining an opening through which the keyway of the lock is accessible.

An object of the invention of the present application is to improve the shutter construction so as to better seal the opening through which the keyway of the lock is accessible. An additional feature of the invention resides in the mounting of the shutter relatively to the lock, and the means whereby the shutter is controlled in its movement relatively to the lock.

As a feature of my invention, I utilize a shutter that is adapted to move relatively to the key hole of the lock, and is equipped with a cover means or seal that moves with the shutter, but is spring pressed relatively thereto and into sealing relation to the key hole of the lock.

A further feature of my invention resides in the utilization of a novel form of spring for controlling the movement of the shutter, and for facilitating the assembly of the shutter relatively to the lock body.

I have thus outlined my invention in order that its relationship to the prior art and to the invention of my earlier application may be clearly understood. There are of course features of my invention that I have not as yet referred to, but they will be fully set forth in the specification that follows and will be claimed in the claims appended hereto. Naturally, those skilled in the art will readily conceive various structural means for utilizing my invention, so that my invention should not be limited to the specific structure I shall herein illustrate and describe.

Referring now to the drawing, where a preferred form of my invention is shown, Fig. 1 is a perspective view of a typical cylinder lock to which my invention may be applied. Fig. 2 is a front view of the lock of Fig. 1 showing the shutter maintained at one side. Fig. 3 is a partial vertical section through my lock. Fig. 4 is a sec-

tion taken along lines 4—4 of Fig. 3. Fig. 5 is a view of certain parts of Fig. 4 illustrating the relationship of the parts when the shutter is moved to its position of Fig. 2. Fig. 6 is an exploded view showing the construction of the front end of my lock and the scalp applied thereto. Fig. 7 is an exploded view of the parts of the shutter.

Referring now more particularly to the drawing, a cylinder lock to which my invention may be applied is designated by reference numeral 10 and is shown bored at 14 for the rotation relatively thereto of a conventional key plug 11 adapted to actuate a connecting bar 12. The front end of the cylinder 10 may be formed as best shown in Fig. 6, with a depressed opening or recess 13 of rather unusual shape. This recess is of course in communication with the bore 14 in which is mounted the key plug 11, the head of the key plug lying within the recess or depression 13. The head of the cylinder 10 is slotted as at 15 for the escape of such moisture as may condense out of the keyway 16 of the key plug 11, all in accordance with the teachings of my patent supra.

25 The head of the cylinder 10 has extending therefrom a post 17 having a bore 18 for a purpose to be hereinafter set forth. Spaced from the post 17 is a partial cylindrical flange 19 terminating at 20 and 21. The cylinder 10 will be manufactured preferably by die casting the same, and it is therefore relatively simple to form it as set forth in the drawing and as just described.

It is preferred in the art to finish the heads of lock cylinders with scalps, this being more economical and more satisfactory than finishing the heads proper. The scalp for my lock is designated by reference numeral 25, and is formed of sheet metal preferably chromium plated, and equipped with lugs 26. An opening 27 is formed

40 in the scalp 25 for alignment with the bore 14 of the cylinder lock, and a second opening 28 is formed for the passage of the cylindrical flange 19. The scalp 25 is placed over the head of the cylinder lock 10 as best illustrated in Fig. 3 and is held assembled to the head in the usual manner well known in the art through the lugs 26.

45 It is well at this point to indicate that while I prefer to utilize the scalp 25, and shall illustrate my novel key hole cover cooperating with the scalp, those skilled in the art will appreciate that my invention may be utilized in a lock of the class described not having a scalp.

The key hole shutter and the key hole seal of my invention are best shown in Figs. 1 and 7. In Fig. 7 the shutter is designated by reference nu-

meral 30 and is formed with a partial flange 31 terminating at 32 and 32a. The shutter 30 is adapted for insertion over the post 17 of the lock 10, and to lie with its flange 31 resting against the inner surface of the flange 19 of the lock. Prior to the placing of the shutter 30 over the post 17, a spring 33 is placed over the post 17 and into its position of Figs. 4 and 6. The spring 33 is preferably of the torsion type, and is adapted to be held in a partially wound or tensioned position with one leg 34 against surface 20 of the flange 19 and with its other leg 35 against the surface 21 of the flange 19.

When the shutter 30 is assembled relatively to the lock by insertion over the post 17, surface 32a of its flange 31 will lie against the leg 34 of the spring 33 while its surface 32 will lie against the leg 35 of the spring 33. It is obvious that with this relation of the parts, the shutter 30 will be held yieldingly in its central position of Fig. 1 and against pivotal movement about the post 17. For preventing endwise movement of the shutter 30 off the post 17, a headed pin 40 is utilized as best shown in Fig. 3. This headed pin 40 is forced into the bore 18 of the post 17 and holds the parts assembled as illustrated in Fig. 3.

The inner face of the shutter 30 is formed with a depression 41 within which is mounted a seal 42 in the form of a disk. A spring 43 lies between the seal 42 and the inner surface of the depression 41 and tends to press the seal 42 relatively to the shutter 30 and against a flange 44 outlining the opening 27 of the scalp 25. In Fig. 3, the seal 42 is shown against the flange 44 and in sealing relation to the opening 27. The direct application of the pressure of spring 43 against the seal 42 urging it towards the flange 44, is extremely effective in sealing the opening 27. As a matter of fact, the seal is considerably better than that of my patent supra, although the results obtained from my earlier invention are very superior to those obtained from the earlier seals employed in the art.

When it is desired to obtain access to the keyway 16, the shutter 30 is moved from its position of Fig. 1 to its position of Fig. 2. As the shutter moves to the position of Fig. 2, the surface 32a of the flange 31 will press against the leg 34 of the spring 33 and will move that spring leg to the position of Fig. 5. Fig. 5 shows the position of the spring 33 and cooperating parts when the shutter is in its position of Fig. 2. In Fig. 5 the leg 34 of the spring 33 is shown against the limit surface 21 of the flange 19. In order to further rotate the shutter in the direction in which it is moved to its position of Figs. 2 and 5, it would be necessary to shear the leg 34 of the spring 33. Therefore, it may be said that spring 33 yieldingly limits the throw of the shutter 30. This is a very important feature of the invention as those skilled in the art will fully appreciate.

It is important at this point to note also the ease of assembly of the shutter 30 relatively to the head of the cylinder 10. Thus, because of the type of spring utilized, the mere placing of the flange 31 of the shutter 30 over the post 17, effectively assembles the shutter relatively to the spring 33.

As the shutter moves from its position of Fig. 1 to its position of Fig. 2, the flange 44 will act to cam the seal 42 toward the shutter and out of sealing position, so that the seal may move with the shutter to the position of Fig. 2. In the position of the parts in Fig. 2, the seal 42 is held by the front end of the scalp 25 against movement

away from the shutter and out of the depression 41 thereof because of the pressure of the spring 43.

I believe that the operation and construction of my invention will now be apparent to those skilled in the art.

I now claim:

1. In a lock of the class described, a key hole shutter, means mounting said key hole shutter on said lock for movement relatively to the key hole of said lock, and cover means movable with said key hole shutter and relatively to said key hole shutter for covering the said key hole.

2. In a lock of the class described, a key hole shutter mounted on said lock for movement relatively to the key hole of said lock, and cover means movable mounted on said key hole shutter for movement relatively thereto into covering relation to said key hole, while moving bodily with said key hole shutter relatively to the key hole.

3. In a lock of the class described, a key hole shutter, means mounting said key hole shutter on said lock for movement relatively to the key hole of said lock, cover means movable with said key hole shutter and relatively to said key hole shutter for covering the said key hole, and a spring for pressing said cover means relatively to said key hole shutter and against said key hole.

4. In a lock of the class described, a key hole shutter, means mounting said key hole shutter on said lock for movement relatively to an opening of the lock through which a key is inserted into the key hole of the lock, cover means movable with said key hole shutter and relatively to said key hole shutter for covering the said opening, and the said opening having a sealing outlining surface for sealing cooperation with said cover means.

5. In a lock of the class described, a key hole shutter, means mounting said key hole shutter on said lock for movement relatively to the key hole of said lock, a spring between said key hole shutter and lock for urging said key hole shutter into a predetermined position relatively to said lock, cover means movable with said key hole shutter and relatively to said key hole shutter for covering the said key hole, and a spring for pressing said cover means relatively to said key hole shutter and toward covering relation to said key hole.

6. In a lock of the class described, having a key hole, a key hole shutter, means mounting said key hole shutter on a portion of said lock for movement relatively to said key hole, a key hole seal mounted on said key hole shutter and movable relatively thereto, a spring pressing said key hole seal relatively to said key hole shutter and toward sealing relation to said key hole, and a surface formed on said key hole seal for camming it against the pressure of said spring out of said sealing relation as said seal moves with said key hole shutter.

7. In a lock of the class described, having a key hole, a key hole shutter, means mounting said key hole shutter on a portion of said lock for movement relatively to said key hole, a key hole seal mounted on said key hole shutter and movable relatively thereto, a spring pressing said key hole seal relatively to said key hole shutter and toward a cavity formed about the front end of said key hole, and a sealing surface formed on said key hole seal for sealing contact with the periphery of said cavity whereby effectively to seal said key hole.

8. In a lock of the class described, having a

key hole, a key hole shutter, means mounting said key hole shutter on a portion of said lock for movement relatively to said key hole, a key hole seal mounted on said key hole shutter and movable relatively thereto, a spring pressing said key hole seal relatively to said key hole shutter and toward a cavity formed about the front end of said key hole, a sealing surface formed on said key hole seal for sealing contact with the periphery of said cavity whereby effectively to seal said key hole when said key hole seal is moved with said key hole shutter into position opposite said cavity, and a spring for yieldingly positioning said key hole shutter with said key hole seal opposite said cavity.

9. In a lock of the class described having a front head portion, a torsion spring mounted on said lock and having opposed ends, means on said head portion limiting the throw of each of said ends whereby to hold said spring in an initial position, a key hole shutter having opposed parts cooperable with said opposed spring ends, means mounting said key hole shutter for rotation substantially about the axis of said spring and relatively to the said lock, the rotation of said key hole shutter in one direction being opposed by one of said spring ends while its rotation in a reverse direction is opposed by the other of said spring ends.

10. In a lock of the class described having a front head portion, a torsion spring mounted on said front head portion and having opposed ends, means on said head portion limiting the throw of each of said ends whereby to hold said spring in an initial position, a key hole shutter having opposed parts cooperable with said opposed spring ends, means mounting said key hole shutter for rotation substantially about the axis of said spring and relatively to the face of said front head portion, the rotation of said key hole shutter in one direction being opposed by one of said spring ends while its rotation in a reverse direction is opposed by the other of said spring ends, the rotation of said key hole shutter moving one of said spring ends until it contacts the limit means of the other of said spring ends to limit the rotation of said key hole cover.

11. In a lock of the class described having a key opening for the insertion of a key, a pin extending from said lock body, a shutter pivotally mounted on said pin for pivotal movement relatively to said lock body, a spring placed about said pin and having opposed legs, a portion of said shutter cooperating with one of said legs to move said leg as said shutter is pivoted in one direction, a second portion of said shutter similarly cooperable with the other of said legs when said shutter is pivoted in a reverse direction, and means whereby the movement of said legs is limited to limit the throw of said shutter.

12. In a lock of the class described having a front head portion, a key plug rotatable in a bore formed in said lock body, a scalp assembled on said head portion and having an opening in alignment with the key plug, a shutter mounted on said lock body for movement relatively to said scalp into and out of covering relation to said opening, a seal for said opening movably mounted on said shutter and movable therewith, and a spring for pressing said seal relatively to said shutter and toward sealing relation to said opening.

13. In a lock of the class described having a front head portion, a key plug rotatable in a bore formed in said lock body, a scalp assembled on said head portion and having an opening in alignment with the key plug, a shutter mounted on said lock body for movement relatively to said scalp into and out of covering relation to said opening, a seal for said opening movably mounted on said shutter and movable therewith, and a spring for pressing said seal relatively to said shutter and toward sealing relation to said opening, said seal being formed so as to be cammed by the surface defining said opening toward said shutter and out of sealing relation to said opening when said shutter is moved away from covering relation to said opening.

14. In a lock of the class described, a lock body, a key plug rotatable in said lock body, a scalp, means securing said scalp on said lock body to form an integral part thereof, said scalp having a depressed opening in alignment with said key plug, the periphery of said opening being defined by an inwardly flanged surface, a shutter mounted on said lock body for movement relatively to said scalp into and out of covering relation to said opening, a seal for said opening movably mounted on said shutter and having a flanged head portion corresponding to the periphery of said opening for sealing said opening, and a spring for pressing said seal relatively to said shutter and toward sealing relation to said opening.

15. In a lock of the class described having a front head portion, a spring mounted on said front head portion and having opposed ends, a key hole shutter having opposed parts cooperable with said opposed spring ends, means mounting said key hole shutter for rotation relatively to the face of said front head portion, the rotation of said key hole shutter in one direction being opposed by one of its opposed parts cooperable with one of said spring ends while its rotation in a reverse direction is opposed by the other of its opposed parts cooperable with the other of said spring ends.

THEODORE H. JOHNSTONE.
